CLAIM

The ornamental design for a full phase module gate drive housing, as shown and described.

DESCRIPTION

FIG. 1 is a perspective view of a panel of a full phase module gate drive housing;

FIG. 2 is a first elevational view thereof;

FIG. 3 is second elevational view thereof;

FIG. 4 is a top plan view thereof;

FIG. 5 is a bottom plan view thereof;

FIG. 6 is a third elevational view thereof; and,

FIG. 7 is a fourth elevational view thereof.

The broken line portion of the figure drawings is included to show portions of the article that form no part of the claimed design.
